CABINET HANDLE OR THE LIKE

Dagfinn O. Amdal, Rockford, Ill., assignor to National Lock Company, Rockford, Ill., a corporation of Delaware

Application March 7, 1955, Serial No. 34,887

Term of patent 7 years

(Cl. D10—8)

Fig. 3.

Fig. 5.

Fig. 4.

Fig. 2 is a top plan view thereof;

Fig. 3 is a rear elevation thereof;

Fig. 4 is an end elevation thereof; and

Fig. 5 is an enlarged sectional view taken on the line 5—5 of Fig. 1.

I claim:

The ornamental design for a cabinet handle or the like, substantially as shown.
